STABILIZING GUIDES FOR TABLES

William James Bargen, Waukegan, Ill.

Application December 14, 1953, Serial No. 397,921

2 Claims. (Cl. 45—137)

This invention relates to an improved desk construction.

An object of this invention is to provide an improved desk construction which is designed particularly as a school desk formed out of a tubular frame with stabilizing means at the lower ends of the legs.

Another object of this invention is to provide a tubular frame for a desk having base or stabilizing bars fixed to the lower ends of the legs, with the bars formed of obtusely related portions which form guides for arranging a plurality of desks in symmetrical groups.

Another object of this invention is to provide a tubular frame for a desk having base bars connecting the opposite legs together with cushioned foot or bottom members engageable with a floor to resist sliding and marring of the floor.

A further object of this invention is to provide in a desk or table frame, a pair of leg connecting bars at the lower ends of the legs which project laterally from the vertical planes of the opposite ends of the top so that the connecting bars of adjacent desks or tables will hold the tops against touching.

A further object of this invention is to provide a tubular frame for a desk or table wherein the lower ends of each pair of legs are connected together by means of a connecting bar which is longitudinally bent with obtusely related portions which assist in the group arrangement of the desks or tables.

With the above and other objects in view, my invention consists in the arrangement, combination and details of construction disclosed in the drawings and specification, and then more particularly pointed out in the appended claims.

In the drawings:

Figure 1 is a bottom plan view, partly broken away and in section, of a desk or table supporting structure constructed according to an embodiment of this invention.

Figure 2 is a detailed end elevation, partly broken away and in section, of the base portion of the frame structure.

Figure 3 is a fragmentary sectional view taken on the line 3—3 of Figure 2.

Figure 4 is a sectional view taken on the line 4—4 of Figure 2.

Figure 5 is a diagrammatic view showing one grouping or arrangement of tables embodying this invention.

Figure 6 is a diagrammatic view showing another grouping or arrangement of tables embodying this invention.

Figure 7 is a diagrammatic view showing a further grouping or arrangement of desks embodying this invention.

Figure 8 is a plan view showing a pair of desks disposed back-to-back.

Referring to the drawings, the numeral 10 designates generally a frame structure having a top 11 secured to the upper portion thereof by fastening means 13.

The frame structure 10 is formed of pairs of legs 12

2

and 14 which are formed at their upper ends with inwardly convergent substantially horizontal upper portions 15 and 16 respectively.

The horizontal leg portions 15 and 16 are connected together at their inner convergent ends with substantially T-shaped connectors or couplings 17, and the two couplings 17 are connected together by means of a truncated V-shaped connecting bar 18. The legs 12 and 14, at their lower ends, are secured to a base bar, generally indicated at 19.

The upper side of bar 19 is provided with bushings 20 and 21 in which the legs 12 and 14 are firmly secured such as by welding or the like. The bar 19, as shown in Figures 1 and 4, is formed with a relatively long forward portion 22 with an intermediate obtusely related portion 23, and with a rear obtusely related portion 24.

The two intermediate portions 23 are disposed in substantially parallel relation, whereas the long forward portions 22 converge forwardly and the short rear portions 24 converge rearwardly. The angular relation of the forward portion 22 with respect to the intermediate portion 23 is substantially the same as the angular relation of the rear portion 24 with respect to the intermediate portion 23, the purpose for which will be hereinafter described.

A cushioning shoe, generally indicated at 25, is secured to the lower side of the bar 19 by fastening means 26. The cushioning means or member 25 is formed of a flat embedded bar 27 having a configuration similar to bar 19, and bar 27 is embedded in a rubber covering 28. The covering 28, at the opposite ends thereof, is provided with foot members 29 and 30.

As shown in Figure 1, the opposite ends of the top 11 are disposed inwardly of the vertical plane of the outer edges of bars 19 so that when these frame structures, with the top secured thereto, are placed in various kinds of groups the tops 11 will not be in contact one with another.

The frame structure hereinbefore described may be grouped in a circular arrangement of the desks with the rear portions of the desks outermost, as shown in Figure 5. In this arrangement the child seated at the desk will be on the outside of the circle.

Where it is desired to have the children on the inside of the circle, the desks are arranged with the short rear portions 24 in abutting relation, as shown in Figure 6. In the event it is desired to position the desks in substantially a straight line, the intermediate portions 23 will be disposed in abutting relation as shown in Figure 7.

The base bars 19 not only provide a stabilizing means for holding the legs 12 and 14 against vibration or undue strain, but also provide a rest for the feet of the child, in addition to providing a guide means for the instructor in arranging a series of these desks or tables in a particular group configuration.

This frame structure is preferably formed out of tubular material which will provide the necessary strength with reduction in weight, and at the same time provide a sturdy frame structure which will withstand hard usage.

The upper ends of the legs 12 and 14 are connected together by means of a tie bar 31 which is welded or otherwise firmly secured to the junction between the legs 12 and 14 and the horizontal inwardly convergent upper end portions 15 and 16 respectively.

The stabilizing guides herein disclosed may be used with table tops of various shapes. While the legs are shown as being tubular they may be made solid and formed out of either metal or wood.

The guides not only provide for spacing desks from each other, but also take the place of rungs heretofore used for strength purposes in connecting legs together. The

arrangement of the legs, particularly the front legs, which are set back, tends to open up leg room in conjunction with a chair.

The guides may be used alone with the table or desk structure, or may be used with the rubber shoes.

What is claimed is:

1. In a desk or table frame, a pair of flat oppositely disposed base bars, a pair of legs secured to and extending upwardly from each of said base bars, means connecting the upper ends of the legs of each pair of legs, said bars each being formed of a relatively long inwardly inclined forward portion, an obtusely related intermediate portion extending from the rear of said forward portion, and an obtusely related rear portion extending from the rear of said intermediate portion, the forward portions of said bars converging forwardly, said intermediate portions of said bars being substantially parallel, and said rear portions converging rearwardly, said pair of legs converging inwardly, and means connecting the upper ends of said pairs of legs together, said base bars each extending outwardly beyond said frame and being adapted to engage the base bar of an adjacent frame to align said frames.

2. In a desk or table frame, a pair of flat base bars arranged in spaced oppositely disposed confronting relation, a tubular framework supported on and secured to

10 said bars and extending upwardly and inwardly therefrom, said base bars each extending outwardly beyond said framework, said bars each being formed with intermediate portions extending generally parallel to each other, forward portions converging forwardly and inwardly and rear portions converging rearwardly and inwardly with the forward intermediate and rear portion of each of said bars being integral, said base bars being adapted to have the outer edge portions thereof engage the outer edge portion of an adjacent bar of an adjacent frame to position said frames in respect to each other in aligned relation.
